VACUUM CLEANER

Axel Albert Forsberg, Stockholm, Sweden, assignor to Electrolux Corporation, New York, N. Y., a corporation of New York

Application April 24, 1942, Serial No. 440,293
In Sweden May 5, 1941

5 Claims. (Cl. 183—51)

My present invention relates to vacuum cleaners, and has for its object to improve the capacity of apparatus of this kind and at the same time simplify their operation.

The accompanying drawings show an embodiment of the invention, and in connection with the following description of said embodiment the characteristics of the invention will be set forth.

Fig. 1 is a vertical longitudinal section of a vacuum cleaner constructed in accordance with the invention.

Fig. 2 is a plan view of the dust container of the apparatus with its cover removed.

Fig. 3 is a side view of said cover placed on supporting members arranged for this purpose.

Figs. 4—6 and 7 show details and a wiring diagram, respectively, of the starting device of the vacuum cleaner motor.

Figs. 8 and 9 show details of the supporting means of the motor fan unit of the apparatus, Fig. 8 being a section along the line 8—8 of Fig. 9.

Figs. 10—14 show different details of the connecting members between the cover of the apparatus and the dust container, Fig. 13 being taken on the line 13—13 of Fig. 12.

Figs. 15 and 16 show details of a cleaning device for the dust filter, Fig. 16 being a section along the line 16—16 of Fig. 15, and

Figs. 17 and 18 show details of said filter itself, Fig. 17 being a section along the line 17—17 of Fig. 18.

As appears from Figs. 1—3, the vacuum cleaner consists of a suitably elongated lower part 10 formed as a dust container, and an upper part 11 of similar shape preferably serving as a cover for the dust container. Connected to the dust container 10 are a number of supporting wheels 12 and 13 for the apparatus, of which two wheels 12 are arranged on horizontal axles rigidly connected to the dust container and suitably located at the rear end of the container. At the front end of the container a wheel 13 is provided with a caster mounting. The motor fan unit 14 of the apparatus as well as dust filters 15 formed in known manner with concentric, circular folds are connected to the cover 11. The motor fan unit and filter are, as appears from the drawings, located side by side. Moreover, the cover is provided with a carrying handle 16 for the apparatus and with an electric plug and switch device 17. The cover 11 thus forms together with the filter, motor fan unit and other electric parts, a unit capable of being lifted off from the dust container 10.

The cover 11 with the members mounted there-

on encloses spaces or chambers communicating with each other. One of these chambers is a suction chamber 18 bounded by the outer wall 19 of the cover, an under wall 20 connected to said outer wall, the filter 15, a cylindrical member 23 connected to or arranged in an opening in the under wall 20, a casing immediately surrounding the motor fan unit 14 within the member 23 and consisting of hoods 28, 29 and 30 suitably removably connected to each other, as well as a partition 21 extending transversely to the longitudinal direction of the vacuum cleaner. The other chamber is a pressure chamber 22 bounded by the hoods 28, 29 and 30, the partition 21 and the outer wall 19 of the cover. Located in the pressure chamber 22, is the motor fan unit including a motor 24 and two fans 25 arranged on the shaft of the motor. The under wall 20 is formed with one or, if desired, two openings for receiving the filter and the member 23, if the latter is not made integrally with said under wall. The inlet of the member 23 is formed by one or more openings 26. The suction and pressure chambers 18 and 22, respectively, communicate with each other by means of an opening 30' made in the hood 30 and serving as an inlet opening for the fans. The partition 21 is suitably tightly connected to the casing surrounding the unit.

The motor 24 is resiliently mounted in rubber rings 27 arranged at its upper and lower ends. Of the hoods 28, 29 and 30 surrounding the unit, the latter two serve as fan hoods. The hoods 28, 29 and 30 have less diameter than the member 23, an annular channel 31 which conducts the air from the openings 26 to the inlet 30' of the fans being thus formed. Inserted between the upper end portion of the hood 28 and parts rigidly connected to the cover 11, such as the partition 21, is a rubber ring 32. A rubber ring 33 is also located between the outer portion of the hood 30, in which is formed the inlet opening 30', and the bottom part of the member 23. The rings 32 and 33 thus form a further resilient support for the unit. The member 23 extends somewhat deeper into the dust container than the hoods 28, 29 and 30, and fulfills a double task, namely to carry the unit 14, on one hand, and, on the other hand, to form a guide for the air current which, after having passed through the filter and the opening 26, flows through the annular channel 31 to the inlet opening 30' of the fan. For this purpose the bearing ring 33 is, as appears from Figs. 8 and 9, formed with a number of guide bars 34 against which the hood 30 bears. Alternate guide

bars are lengthened for improving the guiding of the air. If desired, they may, for this purpose, be bent or tilted.

The member 23 may be provided at its lower outer surface with one or more projections 35 of rubber or other suitable material, said projections serving as feet when the cover 11 is removed from the dust container 10. To the other end portion of the cover, there may be connected one or more legs 36 adapted to cooperate with the feet 35 for supporting the cover in an upright position when outside the dust container, as when the latter is to be emptied.

The filter 15 is provided with a hand-operated cleaning or shaking device of a kind known per se and shown, for instance, in Patent No. 1,946,665 issued February 13, 1938, to Tom C. Bieth. This device is adapted to be actuated by a push-button 37. In order that during the cleaning of the filter, when the motor is in operation, substantially the same pressure should obtain on both sides of the filter, the cover 11 is provided, above the filter, with a valve device 38 through which air may flow through the space 18 directly to the fans, that is without passing through the filters. The valve consists of a hood 39 pivotally connected to the outer wall of the cover, and openings 40 cooperating with said hood and made in part 19 (Figs. 15 and 16). The hood embraces the upper part of the knob 37, the operator being thus forced to open the hood, when the filter is to be shaken. This will cause air to flow directly into the fans. The edge of the hood bearing against the cover is provided with a packing strip 41, for example, of rubber. When the apparatus is in operation, the seal provided by this packing is improved by the atmospheric pressure. The hood is formed with a handle 42 for facilitating the opening thereof. The hinge or hinges by means of which the hood is connected to the cover may suitably be yieldable or consist of a double link or the like so as to permit the edge of the hood bearing against the cover to be adjusted into the proper position relatively to the cover and thus automatically bear against said cover and form a sealing joint against it, independent of variations, if any, in the dimensions of the parts.

To prevent the penetration of dust through the openings formed in the fastening devices at the upper points 43 of the folds of the filter, segments 44 of resilient material are interposed between said filter points and the cross-shaped movable part 45 of the shaking device. The points of the folds are kept in place against the segments 44 by means of metal wires 46 which engage the supporting rings 47 underneath said folds and pass through the resilient segments 44, and are fixed to the movable part 45 by being bent thereover, as is clearly shown in Figs. 17 and 18.

The shank 90 of button 37 carries a flanged member 91 which, as appears more clearly in Fig. 15, is riveted or otherwise suitably secured to the movable part 45. The lower end of shank 90 is reciprocable within a cylindrical guide 92 which is supported on a frame 93. A coil spring 94 is compressed between flanged member 91 and the frame 93 and tends to hold the flanged member, push-button 37 and movable part 45 in their uppermost positions. The frame 93 passes through suitable apertures in the part 45 and is secured to the outer wall 19 of cover 11. This frame carries a circular hoop 95 which serves to support the lower intermediate fold of filter 15. The outer edge of the filter is secured to the

under wall around the opening therein, and the center of the filter is secured to center of frame 93.

When the hood 39 is opened and the button 37 depressed, the part 45 is lowered and hence slack is provided in the folds of the filter. If the button is then released, the spring 94 moves the part 45 quickly upwardly, thus snapping the filter and dislodging dirt from the under side thereof. Even if the motor is running, no air flows through the filter inasmuch as hood 39 is open, and therefore the dislodged dirt settles in the dust container formed by the casing 10.

To prevent the wheels 12 and 13 from damaging furniture or the like, when the apparatus is moved, they are arranged in recesses or pockets 48 and 49 in the walls of the dust container. To prevent as far as possible the dust from being whirled up in the container and to thus facilitate its precipitation in said container, a number of transverse, tilted walls 50 are provided, which extend along the bottom of the container and between its outer walls. These transverse walls also increase the strength of the container. To facilitate the emptying of the container 10, two tubular handles 51 and 52 are arranged at its ends, around the axes of which handles the container may be rotated, when being emptied. One of these handles, namely 51, which is formed with a continuous channel, serves as coupling means for the suction hose of the apparatus, while the other, 52, may be closed. Each handle is formed with a milled collar 53 so as to facilitate said rotation, when the container is being emptied.

Figs. 10-14 show the locking devices by means of which the cover or upper part 11 of the apparatus is connected to the container 10. These locking devices consist each of a clip 54 pivotal about a preferably horizontal pin 57 connected to the cover 11, said clip being suitably made of spring wire. In the locking position the clip 54 cooperates with the handle 51 or 52, respectively, or embraces it by means of a lever 55 of known construction which bears against said handle, preferably against that part of it which is provided with a smaller diameter than the outer part. The ends of the two legs of the clip 54 which are formed as eyes 56 are journaled on the pins 57 in attachments 58 connected to the cover 11. Torsion springs 59 are arranged around these pins 57 and inserted between said attachments and the eyes of the legs. The springs 59 serve to keep the legs directed obliquely outward when not engaging the handles 51 and 52 so as to make it possible to remove the cover from or place it on the dust container without any interference from the handles 51 or 52. The lever 55, which is connected to the straight middle portion of the clip, is provided in a manner known per se with a roller 60 at its end portion bearing against said handle.

The vacuum cleaner is provided with a switch combined with a starting resistance, the resistance having for its object to reduce the surge of current during starting. The construction is such that the resistance is switched in on starting but, as soon as the manually applied force is relieved, the resistance is automatically shunted. The entire starting device, including the starting resistance and switches, is placed in the pressure chamber 22 in such manner that it is cooled by the blowing air. The device which is clearly illustrated by the Figs. 4-7 consists of two switches 61 and 62 and the above-mentioned resistance designated by 63. The switches are

rigidly connected to an insulating piece 64 through which the levers 65 and 66 of the switches pass. This insulating piece 64 is tightly connected to the cover 11 and also forms the bottom of a casing 67 surrounding the connecting contacts 68 of the apparatus. Slidably mounted between the casing 67 and the insulating piece 64 are the hand-operated switch members, namely bars 69 and 70, by means of which the switches are thrown. Said bars which are suitably made of insulating material are slideable in the walls 67 of the casing. As appears from the wiring diagram of Fig. 7, the double pole switch 62 is connected in the leads of motor 24. The resistance 63 is connected in series in one of the leads and the switch 61 is connected to shunt the resistance. In order to return the bar 69 to its initial position after its action, a pressure spring 76 is inserted between a tongue 77 connected to said spring and the casing 67. Moreover, said bars are provided with projections 78 and 79 so that the bar 69, when in operation, entrains the bar 70.

In Figs. 4-7 all parts are shown in the breaking position. The starting device described functions in the following manner: When the apparatus is to be started, the bar 69 is pressed inwardly, thus compressing the spring 76, the switch 61 is opened and the resistance 63 is connected in. Immediately afterwards the 2-pole switch 62 is closed by the bar 70 being entrained by the bar 69. The circuit then consists of the switch 62, the motor 24 and the resistance 63 via the conduits 15, 74, 73, 72 and 71. When the pressure on the bar 69 is relieved, the latter is brought back to its initial position by the spring 76, the switch 61 being closed and the resistance 63 shunted in the circuit. The driving motor of the apparatus is stopped by the bar 70 being actuated in the opposite direction, in which case the switch 62 is opened. As appears from Fig. 6, a clearance 80 is provided between the projections 78 and 79 of the bars 69 and 70, this having for its object to ensure in all conditions that the switch 61 will always be actuated before the switch 62.

What I claim is:

1. In a vacuum cleaner, an elongated casing open at the top and forming a dust receptacle, means forming an air and dust inlet at one end of said casing, a closure for said casing, said closure including an outer top wall and an under wall, said under wall being formed with an opening adjacent said inlet, a dust separating member disposed across said opening, a hollow air tight member depending in air tight relationship from said under wall into said casing, said hollow member being located at the side of said dust separating member opposite from said inlet, a motor fan unit in said hollow member, means including a hand grasp element extending through said outer top wall for shaking said dust separating member, a cover member movably secured to said top wall for covering said element, and means

providing an air-tight seal between said cover member and said top wall when the former is closed, the space inside said cover member being in communication with the space between said top wall and under wall.

2. In a vacuum cleaner, an elongated casing open at the top and forming a dust receptacle, means forming an air and dust inlet at one end of said casing, a removable closure for said casing, said closure including an outer top wall and an under wall, said under wall being formed with an opening adjacent said inlet, a dust separating member disposed across said opening, a hollow air tight member depending in air tight relationship from said under wall into said casing, said hollow member being located at the side of said dust separating member opposite from said inlet, a motor fan unit in said hollow member, and supporting means depending from said under wall in spaced relation to said hollow member and serving, together with said hollow member, to support said closure in an upright position when the latter is removed from said casing.

3. In a vacuum cleaner, a casing having an inlet, a fan for producing flow of air through said inlet, a filter in said casing in the path of air flow between said inlet and said fan, a member for shaking said filter, said casing being formed with a port communicating with the path of air flow between said filter and said fan, and means including a valve for closing said port and rendering said member inoperative to shake said filter, said means being manually operable for rendering said member operable to shake said filter and for opening said port to bypass said filter by providing for direct flow of air through said port to said fan.

4. In a vacuum cleaner, a casing having an inlet, a fan for producing flow of air through said inlet, a filter in said casing in the path of air flow between said inlet and said fan, a manually operable member extending exteriorly of said casing for shaking said filter, said casing being formed with a port communicating with the path of air flow between said filter and said fan, and a movable closure for closing said port and covering said member to render the latter inaccessible for manual operation, said closure being manually movable for rendering said member accessible and for opening said port to bypass said filter by providing for direct flow of air through said port to said fan.

5. In a vacuum cleaner, a casing having an inlet and an outlet, a filter in said casing between said inlet and said outlet, a fan for producing flow of air through said casing, a member for shaking said filter, and means including a valve shiftable between a position interrupting flow of air through said filter and rendering said member operable to shake said filter and a position permitting such flow and rendering said member inoperative to shake said filter.

AXEL ALBERT FORSBERG.
